US0D1043080S

(12) United States Design Patent (10) Patent No.: US D1,043,080 S
Houston, III (45) Date of Patent: * Sep. 24, 2024

(54) SHOE INSERT

(71) Applicant: Telfair W. Houston, III, Atlanta, GA (US)
(72) Inventor: Telfair W. Houston, III, Atlanta, GA (US)

() Term: 15 Years

(21) Appl. No.: 29/908,754

(22) Filed: Jan. 15, 2024

Related U.S. Application Data

(63) Continuation of application No. 29/847,442, filed on Jul. 25, 2022, now abandoned, which is a continuation-in-part of application No. 17/554,116, filed on Dec. 17, 2021, now Pat. No. 11,395,526.
